UNITED STATES PATENT OFFICE

WRISLEY B. OLESON, OF GLEN ELLYN, ILLINOIS, ASSIGNOR TO ALLEN B. WRISLEY COMPANY, OF CHICAGO, ILLINOIS, A CORPORATION OF ILLINOIS

DESIGN FOR A SOAP CAKE

Application filed December 16, 1932. Serial No. 46,468. Term of patent 7 years.

To all whom it may concern:

Be it known that I, WRISLEY B. OLESON, a citizen of the United States, residing at Glen Ellyn, in the county of Du Page and State of Illinois, have invented a new, original, and ornamental Design for a Soap Cake, of which the following is a specification, reference being had to the accompanying drawing, forming part thereof.

Figures 1, 2 and 3 of the drawing are respectively, plan, side and end views of a soap cake, showing my new design.

I claim:

The ornamental design for a soap cake, as shown.

WRISLEY B. OLESON.
